UNITED STATES PATENT OFFICE.

EMIL TYDEN, OF HASTINGS, MICHIGAN.

PEDESTAL-TABLE-LOCKING DEVICE.

No. 893,821.

Specification of Letters Patent.

Patented July 21, 1908.

Application filed March 14, 1908. Serial No. 421,128.

To all whom it may concern:

Be it known that I, EMIL TYDEN, a citizen of the United States, residing at Hastings, in the county of Barry and State of Michigan, have invented new and useful Improvements in Pedestal-Table-Locking Devices, of which the following is a specification, reference being had to the accompanying drawings, forming a part thereof.

10 This invention relates to pedestal extension tables, and particularly, the devices for locking the pedestal members together.

It consists in the features of construction shown and described as indicated in the 15 claims.

In the drawings:—Figure 1 is a vertical longitudinal section of a pedestal extension table containing this invention, the devices being shown in locked position. Fig. 2 is a 20 similar section showing the portion of the table containing the locking devices, the two members being slightly separated as when the table members approach and before they are completely closed together after disengagement of the locking devices and partial separation. Fig. 3 is a section at the line 25 3—3 on Fig. 1. Fig. 4 is a detail elevation of the inner side of the upper end portion of one pedestal member showing the lock-operating device. Fig. 5 is a view similar to Fig. 4 showing a modification.

One of the pedestal members, 1, is provided with studs or posts, 2, 2, jutting inwardly from each of its opposite side walls, 35 designed for engagement of a catch to be carried by the opposite pedestal member for connecting and drawing and securing together the two members of the pedestal. Upon plates, 3, 3, secured to the two corresponding 40 walls of the opposite pedestal member there are fulcrumed bell-crank levers, 4, 4, having each an arm, 4^a, depending from the fulcrum and an arm, 4^b, extending off from the fulcrum outwardly,—that is,

45 away from the meeting plane of the pedestal members. To the depending arm of each lever, there is pivoted a latch, 5, extending inward,—that is, toward and across the parting plane,—adapted for engagement with

50 the post, 2, of the corresponding wall of the opposite pedestal member. From the other arm, 4^b, of each bell-crank lever connecting rods, 6, 6, extend upward within the pedestal, said connecting rods, 6, 6, being connected respectively to the opposite ends of an evener, 7, which is loosely connected

midway between the connecting rods to a bell-crank lever, 8, fulcrumed in a chair or bracket, 9, mounted at the top of the pedestal member and preferably provided with a spring, 10, reacting against a tail-piece, 8^a, of the bell-crank lever for rocking the lever to swing its inner end downward and thrust downward the connecting rod, 6.

An operating rod, 11, is connected to the upstanding arm, 8^b, of the bell-crank lever and extends off toward one end of the table where it may be connected with any suitable means for actuating it and locking it, as the hand lever, 12, to which the rod, 11, is connected at a point so situated with respect to the fulcrum of the hand lever as to be carried into line behind or outward from said fulcrum when the hand lever is swung outward and upward to a position at which it is stopped against the table top or in any other convenient manner. The latch, 5, has at its pivoted end a heel projection, 5^a, extending upward forming a shoulder which encounters a stud, 3^a, projecting from the plate, 3, when the bell-crank lever, 4, is rocked for swinging its depending arm inward,—that is, toward the parting plane of the pedestal members,—and such encounter causes the latch, 5, to be lifted to the position shown in Fig. 2, disengaging it from the stud on the pedestal member, such encounter of the shoulder of the heel, 5^a, with the stud, 3^a, and consequent lifting of the nose of the latch, occurring, it will be seen, after the latch has been thrust inward by the swinging of the bell-crank lever as described, and after said latch is thereby rendered free from frictional engagement with the stud so that it can be easily lifted.

The operation of the device for engaging and drawing the pedestal members together and for locking them when firmly drawn together will be obvious from the foregoing description.

The purpose of the evener, 7, is to compensate for any inequality in the connections of the two latches at opposite sides or any inequality in the fitting to each other of the two sides of the pedestal which might, in the absence of some provision to the contrary, cause one side to be drawn together by the latch and stud at that side while the pedestal members were still separated at the other side. The pivoting of the evener, as described, causes the two sides to be closed up without regard to such inequalities within the range of adaptation of the device, because as soon

as one side is closed, no more drawing being possible through the end of the evener connected with the latch at that side, the entire rocking action of the bell-crank lever, 8, 5 must take effect in drawing the other side, the evener rocking on the bell-crank lever, the connection of such evener with the connecting rod at the side which is already closed becoming the fulcrum and causing the 10 opposite end to give double movement to its connecting rod.

When the lock is to be operated in a table which has the table-top members extensible relatively to their respective pedestal members;—that is, so that the top can be opened 15 up without opening the pedestal,—it may not be necessary to provide connections extending off to the end of the table for operating the device, and in order that it may be 20 conveniently operated and locked without such connections, the form of the evener and the lever on which it is mounted may conveniently be changed as shown in Fig. 5, in 25 which the evener, 7^x, is pivoted to a bell-crank lever, 8^x, mounted on a bracket, 9^x, for rocking transversely of the table,—that is, parallel with the parting plane,—the operating handle arm, 8^y, of the bell-crank lever being thrown from horizontal or approxi- 30 mately horizontal position at one side of its fulcrum to a point a little past horizontal position at the other side for carrying the pivotal connection of the evener, 7^x, to the depending arm of said bell-crank lever from a 35 point below the fulcrum to a point above the fulcrum a little past the vertical line therethrough where it is located by the stopping of the handle arm, 8^y, on the bracket, 9^x.

I claim:—

40 1. In a pedestal extension table, in combination with the two pedestal members, two latching devices for connecting the pedestal members together situated at opposite sides of the axis of the pedestal and each 45 comprising two elements adapted to engage, one mounted upon each pedestal member, said elements on one pedestal member being movable thereon for drawing the pedestal members together after engagement; an evener carrier mounted on said pedestal member; an evener pivoted intermediate 50 its ends to such carrier; operating connections from the opposite ends of the evener to said movable latching elements respectively, and means for operating the evener carrier.

2. In a pedestal extension table, in combination with the separable members of the pedestal, two separate pedestal-connecting 60 devices for drawing the pedestal members together extending across the parting plane located at opposite sides of the axis of the pedestal; an evener carrier mounted on the pedestal; an evener pivoted thereon; sepa- 65 rate operating connections from the oppo-

site ends of the evener to said separate pedestal-connecting devices respectively, and means for actuating the evener carrier.

3. In a pedestal extension table, in combination with the separable members of the 70 pedestal, two separate pedestal-connecting devices for drawing the pedestal members together extending across the parting plane located at opposite sides of the axis of the pedestal; an evener carrier; an evener pivoted thereon; separate operating connections from the opposite ends of the evener to said separate pedestal-connecting devices respectively, and means for actuating and locking the evener carrier. 80

4. In a pedestal extension table, in combination with the two pedestal members, bell-crank levers fulcrumed on the opposite sides of one of said pedestal members; latches pivoted to said bell-crank levers respectively; means on the opposite pedestal members for engaging the latches; connecting rods extending from the bell-crank levers upward within the pedestal; an evener at the upper part of the pedestal to whose 85 opposite ends said rods are connected; a carrier to which the evener is pivoted mounted on the pedestal at the upper part, and means for operating the carrier. 90

5. In a pedestal extension table, in combination with the two pedestal members, bell-crank levers fulcrumed on the opposite sides of one of said pedestal members; latches pivoted to said bell-crank levers respectively; means on the opposite pedestal 100 members for engaging the latches; connecting rods extending from the bell-crank levers upward within the pedestal; an evener at the upper part of the pedestal to whose opposite ends said rods are connected; a lever fulcrumed at the upper part of the pedestal and on which the evener is pivotally mounted between the rod connections; means for rocking the lever over its fulcrum and for securing it at one limit of its rocking 110 movement. 105

6. In a pedestal extension table, in combination with the two pedestal members, bell-crank levers fulcrumed on the opposite sides of one of said pedestal members; 115 latches pivoted to said bell-crank levers respectively; means on the opposite pedestal members for engaging the latches; connecting rods extending from the bell-crank levers upward within the pedestal; an evener 120 at the upper part of the pedestal to whose opposite ends said rods are connected; a lever fulcrumed at the upper part of the pedestal and on which the evener is pivotally mounted between the rod connections; an 125 operating rod connected to the lever and extending toward one end of the table top, and means at said end for locking the rod at one limit of its longitudinal movement for operating the lever. 130

7. In a pedestal extension table, in combination with the pedestal members, a bell-crank lever fulcrumed on one pedestal member having a depending arm; a latch pivoted to said depending arm; means on the opposite pedestal member for engaging said latch, the latch being provided near its pivot with a shoulder, and a stud fixed with respect to the fulcrum of the bell-crank lever

5 10 in position to be encountered by the shoulder when the lever is operated for thrusting

the latch toward the parting plane, and means connected with the other arm of the bell-crank arm for so operating the lever.

In testimony whereof, I have hereunto set 15 my hand at Chicago, Illinois, this 28th day of February, 1908.

EMIL TYDEN.
